(57) CLAIM

We claim the ornamental design for a housing for an interactive aerial display system, as shown and described.

DESCRIPTION

FIG. 1 is a front isometric view of a housing for an interactive aerial display system;

FIG. 2 is a left side view thereof (the right side being a mirror image);

FIG. 3 is a front view thereof;

FIG. 4 is a top view thereof; and,

FIG. 5 is a back view thereof.
